MERCURY SWITCH RELAY

Clarence E. Gehrand, Elkhart, Ind., assignor to
 The Adlake Company, a corporation of Illinois
 Application September 25, 1939, Serial No. 296,346

8 Claims. (Cl. 200—97)

This invention relates to mercury switch relays and, in order to understand the purpose and objects of the invention, it is necessary to define certain terms that will be used.

Normal operate time is the time required to produce a change in the electric circuit through the switch when the relay winding is suddenly closed while all parts of the switch are lying in stable equilibrium.

Normal release time is the time required to produce a change in the electrical circuit through the switch when the relay winding is suddenly opened while all parts of the switch are lying in stable equilibrium.

Normal operate recycling time is the minimum period during which the relay winding must be permitted to remain open in order that the normal operate time is obtainable when the relay winding is suddenly closed. Usually, though not always, the normal operate recycling time is the same as the time required for the switch elements to reach stable equilibrium after the relay winding has been opened.

Normal release recycling time is the minimum period during which the relay winding must be permitted to remain closed in order that the normal release time is obtainable when the relay winding is suddenly opened. Usually, though not always, the normal release recycling time is the same as the time required for the switch elements to reach stable equilibrium after the relay winding has been closed.

Quick operate reset refers to the ability of a switch to give normal operate time without requiring a particular time interval to precede the closing of the relay winding.

Quick release reset refers to the ability of a switch to give normal release time without requiring a particular time interval to precede the opening of the relay winding.

Obviously in writing commercial specifications for relays of this kind, minimum and maximum values are often given for operate and release times, these values representing time intervals which must be met regardless of the relative positioning of the switch parts (i. e., in stable equilibrium or not) at the instant that the condition of the electrical circuit through the relay winding is changed. The minimum values are usually specified to prevent an immediate change in circuit condition in the event of subnormal recycling conditions, and the maximum values are usually given to hold the operation of the relay to reasonable cycles or to some other special operating condition.

With the above definitions in mind, it is broadly the object of this invention to provide a mercury switch relay that can fulfill certain relay specifications that have heretofore been impossible to meet, at least with relays of this type.

It is a further object of this invention to provide these desirable characteristics in a mercury switch relay through the use of two time delay elements used in such a way that their action is correlated and the action of one modifies or affects in some way the action of the other.

More specifically, it is an object of this invention to provide a mercury switch relay which is capable of meeting certain minimum operate and release time requirements and, furthermore, which may embody quick reset features in certain recycling circuits under particular conditions.

Further and other objects and their resultant advantages will become apparent as the disclosure proceeds and the description is read in conjunction with the accompanying drawings, in which—

Fig. 1 is a vertical section illustrating a mercury switch of the front contact type showing the parts in stable equilibrium with the coil de-energized and contacts open;

Fig. 2 is a similar view of the same switch illustrating the parts in stable equilibrium with the coil energized and the contacts closed;

Fig. 3 is a diagrammatic illustration of a circuit which can advantageously use a relay of the type shown in Figs. 1 and 2;

Fig. 4 is a vertical section of a back contact type switch illustrating the parts in stable equilibrium with the coil deenergized and contacts closed or bridged; and

Fig. 5 is a similar view illustrating the parts in stable equilibrium with the coil energized and the contacts open.

It will be understood by those skilled in the art that the following description given in connection with the drawings illustrates and describes preferred embodiments of this invention and that variations may be made in the details of construction without departing from the spirit and scope of the invention as defined in the claims.

Front contact relay (Figs. 1 and 2)

The relay shown in Figs. 1 and 2 has in general the following characteristics: Normally open contact (i. e., a front contact switch); slow make, retarded break; and substantially quick operate reset. The switch illustrated is designed to make

or bridge contacts in 3.5 seconds and to break or open contacts in 0.6 second.

The relay employs a time delay element comprising a gas leak in a thimble associated with one electrode and a second time delay element comprising a mercury cup leak associated with the same electrode. The switch has a quick or automatic reset when used in certain recycling circuits and when the mercury leak is faster than the gas leak.

The relay as shown in Figs. 1 and 2 comprises a coil 10 provided with spaced poles 11 and 12 within which the relay switch generally designated 13 is suitably mounted. The switch 13 comprises a switch envelope 14 preferably of low expansion boro-silicate glass through the base of which lead-ins 16 and 17, preferably of molybdenum or tungsten, are pinch-sealed. The lead-ins extend upwardly into the switch envelope and are provided with insulating sleeves 18, the sleeve 18 surrounding the lead-in 17 being interrupted to expose a portion 17a of the lead-in 17 to the mercury fill 19 in the envelope 14. The two leads 16 and 17 terminate in the electrode portions 21 and 22, respectively, which are adapted to be bridged and unbridged by appropriate manipulation of the mercury fill 19 in a manner to be described.

A glass thimble generally designated as 25 is telescoped over the electrode portion 21 and is fused to the upper end of the stem 18 as indicated at 26. The thimble is provided with a relatively large opening 27 at one side to permit the mercury to pass freely to and from the thimble except only as the movement of the mercury is retarded, when the opening 27 is closed, by the action of a time delay element 28 in the upper end of the thimble. This element consists of a gas pervious cylinder of ceramic material, preferably Alundum Grade RA 98, bonded by fusion or other suitable means into an opening provided in the upper end of the thimble. The cylinder, therefore, offers a predetermined impedance to the flow of gas therethrough in accordance with the exposed portion of the cylinder whenever the mercury in the envelope completely covers the opening 27. The cylinder 28 is, of course, impervious to mercury.

The electrode portion 21 of the lead-in 18 extends above its insulating sleeve 18 into the interior of the thimble 25 where it is surrounded by a ceramic cup 31 bonded to the upper end of said insulating sleeve. The cup forms a reservoir for a small pool of mercury which is always in contact with the electrode portion 21 and permits the bridging of the electrodes 21 and 22 to be accomplished by a mercury to mercury contact.

Fused to the upper portion of the sleeves 18 is an insulating sleeve or cylinder 33 which extends upwardly surrounding the electrode portion 22 and the major portion of the thimble 25. This sleeve is open at its upper end and is provided with a mercury leak or opening 34 in its side adjacent the lower end of opening 27 thus forming a mercury leakage time delay cup. The opening 34 is always below the mercury level and for most uses and circuits it is advantageous to have time delay action of the mercury leakage through the opening 34 shorter than that of the gas leakage through 28.

The mercury fill 19 within the envelope is manipulated by a magnetically controlled plunger or displacer generally designated as 35 and which comprises an iron sleeve 36 telescoped over a glass or ceramic cylinder 33. This iron sleeve

comprises the armature and may be split along one side if desired for operation with alternating current. The sleeve or armature is guided for movement within the envelope by a guide washer 37 adjacent each end of the armature and held thereon by coiled springs 38 which have their end convolutions telescoped and frictionally engaging the end portions of the armature 36. These springs also serve to cushion the armature within the glass envelope.

The switch envelope 13, before being sealed, is completely evacuated and then filled with a suitable inert gas such as helium, hydrogen, or the like, or a mixture of such gases.

Operation of front contact relay

The two final positions of stable equilibrium of the switch parts of the front contact type are illustrated in Figs. 1 and 2, and the movement and operation of the switch from one position to the other is as follows:

Assume that the switch parts are in stable equilibrium with the coil deenergized as shown in Fig. 1 and that the coil is then suddenly energized. Immediately upon energization of the coil the displacer 35 is lowered to the position of Fig. 2. Because the opening 34 in the sleeve 33 is submerged in the mercury fill when the parts are in stable equilibrium and remains submerged as the displacer is lowered, the opening has no effect upon the normal operate time. In other words, when the displacer moves from the Fig. 1 position to the Fig. 2 position, the mercury fill throughout the entire envelope first rises to a position at approximately the top edge of the opening 27 in thimble 25 after which the mercury in the outer portion of the envelope rises to slightly above line 48 of Fig. 2 while the mercury within the thimble, remains temporarily at the lower level due to compression of the gas in the top portion of the thimble. This compressed gas prevents the immediate rise of the mercury in the thimble and, accordingly, prevents bridging of the contacts 21 and 22. Due to the pressure differential in the envelope and the thimble, the gas in the thimble slowly leaks through the porous sleeve 28 at a predetermined rate that is dependent upon the porosity of the sleeve, thus permitting the mercury to rise slowly in the thimble until it finally flows into the ceramic cup 31, bridges with the mercury in the cup 31, and thus completes the circuit through the switch. If the relay coil remains energized, the mercury then levels off to the position shown in Fig. 2.

The time that is required for the inside mercury level to reach the top margin of the ceramic cup 31 and make contact with the mercury therein is determined solely by the impedance which the time delay element or cylinder 28 in the thimble offers to the passage of gas escaping from the thimble. The exposed portion of this element and its porosity are chosen so as to effect a total lapse of time such that the time required for the mercury to rise from the upper edge of the opening 27 to the upper edge of the ceramic cup 31 and into contact with the mercury pool in the cup is equal to the specified normal operate time of the relay which, in the switch illustrated, is 3.5 seconds.

Assume now that the switch parts are in stable equilibrium with the contacts bridged and the coil energized, as shown in Fig. 2, and that the coil is then suddenly deenergized. Immediately the displacer rises to the Fig. 1 position due to its buoyancy and the outside mercury drops to a

position just above the opening 27. The mercury within the thimble 26 is momentarily retained at a level just above the top of the cup 31 and in position to bridge the electrodes due to the presence of the cylinder 33, which causes a mercury seal to be retained around the opening 27. The mercury, however, in the cup 33 tends to level off with the mercury outside of that cup, by flowing through the opening or leak 34, but the mercury within the thimble 26 is held in contact with the mercury in the electrode cup 21 by the surface tension of the mercury and the partial vacuum in the thimble. This condition can obtain for a limited period of time only, and if the breaking of the circuit is not to be made dependent upon uncontrollable variables, it is quite important for the time delay action of the mercury leakage element 34 to be shorter than the corresponding action of the gas leakage element 28. In the illustrated relay, the specified normal release time is 0.6 seconds. This means that 0.6 seconds is required for the mercury level to drop from the top of the cup 33 to the top of the opening 27, and as soon as this happens, gas enters the thimble through the opening 27, effectively bypassing the gas leakage element 28, and causing the mercury level in the thimble 26 to immediately fall to the position shown in Fig. 1, thus breaking the circuit through the switch.

The use of the mercury cup time delay in combination with the gas time delay on the fixed thimble makes it possible to obtain certain relay characteristics that would otherwise be unobtainable. With such an arrangement, a front contact relay can be provided having a normal operate time (the time necessary for the mercury to rise from stable equilibrium above the opening 27 to bridging condition) of ten seconds, for example, after which the mercury levels off at a point higher than bridging level. This can be obtained by the proper selection of the gas leak 28 and the distance between the top of the opening 27 and the edge of the mercury cup 31. The same relay can have a normal release time (the time necessary for the mercury to drop from stable equilibrium after bridging to unbridging position) of two seconds, for example, by properly selecting the distance between the inner top wall of the thimble 26 and the upper edge of the mercury cup 31. By making the opening 34 of proper size and the wall 33 of appropriate height, the mercury seal may be maintained at the upper margin of opening 27 for slightly more than two seconds, after which the seal is broken and the mercury contact at the cup 31 is opened. The relay, therefore, is characterized in this instance by having a normal operate recycling time of three seconds, or thereabouts and a normal release recycling time of thirteen seconds, or thereabouts, with normal operate and release times of ten and two seconds, respectively. The foregoing characteristics could not be obtained without the combined action of two time delay elements.

The relay described in connection with Figs. 1 and 2 may be used to advantage in a recycling circuit, such as is disclosed in Fig. 3, because different time delay elements, though correlated, are used to control operate and release times. The circuit is intended to be a continuously energized circuit and one in which the relay is recycled through its own contacts. The circuit, of course, is merely illustrative of many such circuits that require relays of unusual operating

characteristics, or the kind which the present relay possesses.

Referring to Fig. 3, a load is illustrated at 45 which is controlled by the combined action of a mercury time delay relay 13, illustrated diagrammatically and having the time delay characteristics previously described (3.5 seconds to close and .6 second to open with quick operate reset) and a fast acting or quick make and quick break, back contact relay 46. The relay 13 is, of course, of the front contact type and has its coil connected across the continuously energized leads 41, but in series with the contacts 48 of the relay 46. The coil of the quick acting relay 46 is connected to the leads 47 through the contacts 21 and 22 of the mercury relay 13 as is also the load 45.

Upon energizing the leads 47, the relay 13 is energized through the normally closed back contacts 48 and closes contacts 21 and 22 after the predetermined normal operate time of 3.5 seconds. Closing of the contacts 21 and 22 energizes relay 46 and the load 45. Relay 46, however, is a quick make, quick break relay which, immediately upon energization, opens its contacts 48. This results in deenergization of the operating coil of relay 13 which reopens contacts 21 and 22, after a certain minimum release time for the relay 13 which, in the present instance, is 0.6 second.

Stated in other words, energization of leads 47, if sustained a sufficient length of time, causes the load 45 to be operated for a given interval of time, namely, the minimum release time for the relay 13, but this operation of the load occurs only after a given time interval has elapsed subsequent to the energization of leads 47, the time being the normal operate time of the relay 13. Thus, the normal operate time of the relay 13 can be selected and the normal release time can be chosen so as to give desired operating and non-operating periods to the load.

In addition to these characteristics, relay 13 has substantially quick operate reset characteristic in the illustrated circuit for reasons given below so that if the leads 47 are first energized and then deenergized before the contacts 21 and 22 have had an opportunity to close, the prescribed normal operate time will elapse between the second energization of the leads 47 (if not within 0.6 second) and the closing of the contacts 21 and 22. This is true of the relay 13 in the illustrated circuit when the mercury leak is substantially greater than the gas leak so that the former controls the normal release time. This results in a quick operate reset so that normal operate time will be obtained even under subnormal operate recycling conditions.

Operation of the relay 13 when in the circuit arrangement of Fig. 3 may be explained as follows:

Assume that the coil 10 has been energized, thus causing the displacer to be lowered from the Fig. 1 to the Fig. 2 position, but that the coil is deenergized before the mercury has had time to bridge electrodes 21 and 22, after which the coil 10 has been reenergized (but not before 0.6 second has elapsed). As soon as the coil is deenergized, the displacer rises. The mercury in the outer portion of the envelope does not continue to rise with the displacer, but drops. Due to the fact that the mercury leak is greater than the gas leak, the mercury rapidly drops below the upper edge of the opening 27 and permits gas to enter the thimble and restore the

mercury to the level of Fig. 1 so that, upon re-energization of the coil 10, a full normal operate period will take place, even under subnormal operate recycling conditions described.

5 *Back contact relay—Figs. 3 and 4*

The relay shown in Figs. 4 and 5 has, in general, the following characteristics: Normally closed contact; slow make, retarded break; and 10 substantially quick release reset. Here again, the switch illustrated is designed to make or bridge the contacts in 3.5 seconds, and to break or open the contacts in 0.6 second. Also, the relay employs two time delay elements comprising 15 a gas leak in the thimble and a mercury leak associated with the plunger or displacer.

The relay shown in Figs. 4 and 5 is similar to that shown in Figs. 1 and 2, except that the parts are somewhat differently proportioned, 20 the main difference being that the electrodes and thimble are positioned lower in the envelope by shortening the stem 18. The elements of the relay are substantially the same and are therefore given the same reference characters.

25 Briefly, the relay comprises a coil 10 provided with spaced poles 11 and 12 within which the glass envelope 14 is positioned. Leads 15 and 16 extend upwardly through the sleeve or stem 18 and have electrode portions 21 and 22 which are adapted to be bridged and unbridged by appropriate manipulation of the mercury fill 19.

A glass thimble 25 is fused to the upper end of the stem and surrounds the electrode 21, being provided at its lower end with an opening 35 27 and at its upper end with a time delay gas pervious element 28. A mercury leakage time delay cup is provided by a cylinder 33 which is also fused to the stem 18 and is provided with the mercury leakage opening 34. In most cases, 40 it is desirable to make the mercury leak greater than the gas leak.

The mercury fill 19 is manipulated by a magnetically controlled plunger or displacer 35 comprising an iron sleeve or cylinder 36 guided for 45 longitudinal movements in the envelope by spider washers 37. The sleeve is cushioned by springs 38 as previously described.

Operation of back contact relay

50 The two final positions of stable equilibrium of the switch parts of the rear contact switch relay are illustrated in Figs. 4 and 5, and the movement and operation of the switch from one position to the other is as follows:

55 Assume that the switch parts are in stable equilibrium with the contacts bridged and the coil deenergized, as shown in Fig. 4, and that the coil is then suddenly energized. Immediately upon energization of the coil, the displacer 35 is raised to the position of Fig. 5 and the mercury outside of the cylinder 33 drops to a point above the opening 34. The mercury within the thimble, however, cannot drop immediately due to the mercury seal retained around the opening 27 by reason of the wall 31, and the partial vacuum created in the upper portion of the thimble. Therefore, lowering of the mercury within the thimble 25 is retarded temporarily until sufficient mercury has passed 60 through the leak 34 to lower the level of the mercury below the upper margin of the opening 27, whereupon gas enters the thimble, and the mercury immediately drops and opens the switch contacts. The period required for the mercury 65 to lower in the thimble sufficiently to open the

contacts is controlled by the mercury time delay leak through the opening 34 and is the normal operate time which, in the illustrated relay, is 0.6 second. The mercury finally levels off and the parts assume the positions of stable equilibrium illustrated in Fig. 5.

Assume now that the parts are in stable equilibrium, as shown in Fig. 5, with the contacts open or unbridged and the coil energized and that, under these conditions, the coil is suddenly deenergized. The plunger or displacer immediately drops into the mercury which immediately rises to the level of the lower margin of the opening 27. When the mercury has reached this level, the outer mercury being unrestricted continues to rise, but the mercury within the thimble cannot rise immediately due to the gas pressure created in the upper portion of the thimble. The gas pressure in the upper portion of the thimble then being higher than the gas pressure in the envelope, the pressures tend to equalize by leakage of the gas through the time delay element 28. This leakage permits the mercury to rise slowly in the thimble until it finally flows into the ceramic cup 31 and bridges the contacts. 95 The time that is required for the inside mercury to reach the top level of the ceramic cup 31 and bridge the contacts is determined solely by the impedance which the time delay element or cylinder 28 in the thimble 30 offers to the passage of gas escaping therethrough, and this time is the normal release time. After the contacts are bridged, the mercury levels off to the level of Fig. 4. In the relay illustrated, the positioning of the parts has been so selected 35 and the porosity of the gas leak so chosen that the normal release time is 3.5 seconds.

Like the front contact switch or relay, the back contact switch may be used in a recycling circuit in which the relay is recycled through its 40 own contacts if such operation is desired. Such a circuit would be like that of Fig. 3 in principle, but, of course, somewhat different in detail, as will be obvious to those skilled in the art.

It will be apparent to those skilled in the art 45 that, in both front and back contact forms of the invention, any limitation in quick reset characteristics of the switches may be avoided by the use of the switches in circuits in which the recycling of the relay is controlled by the relay 50 contacts and by making the mercury leak appreciably greater or faster than the gas leak, i. e. by making the time delay caused by the mercury leak appreciably less than the time delay caused by the gas leak.

The combination of a gas time delay in the fixed thimble with the mercury time delay in the mercury cup makes it possible to obtain time delays on both the opening and closing of the contacts with a much greater range of flexibility than it is otherwise possible to obtain. The combination of two time delays is of even greater advantage when the time delays on both make and break have to be held to very close limits, due to the fact that the individual time delays or leaks may be adjusted independently without one materially affecting the other.

Another way to describe the function of the two time delay elements is to say that by their use, the relay is able to have time delay action both when closing and when opening the circuit through the switch, and yet have a quicker reset action than would be possible had only one time delay element been used.

We claim:

1. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a gas leakage device fixed with respect to one of said electrodes and arranged to control the movement of mercury toward said electrode and the other one of said time delay elements comprising a mercury cup provided with a restricted wall opening for the timed passage of mercury arranged to control the movement of mercury away from an electrode, whereby the switch is characterized by a delayed make and a delayed break of the circuit through the electrodes.

2. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a gas leakage device fixed with respect to one of said electrodes and arranged to control the movement of mercury toward said electrode and the other one of said time delay elements comprising a mercury cup extending over a portion of said gas leakage device and provided with a restricted wall opening for the timed passage of mercury arranged to control the movement of mercury away from said electrode, whereby the switch is characterized by a delayed make and a delayed break of the circuit through the electrodes.

3. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting the mercury level, cooperating time delay elements associated with one of said electrodes to delay the movement of mercury with relation to said electrode upon a change in the condition of the electrical circuit through the coil, one of said time delay elements comprising a gas leakage device fixed with respect to one of said electrodes and the other comprising a relatively fixed mercury leakage device, and means including at least one of said time delay elements for insuring that, once the electrodes have been bridged with mercury, they will remain bridged for at least a brief period of time.

4. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting the mercury level, cooperating time delay elements associated with one of said electrodes to delay the movement of mercury with relation to said electrode upon a change in the condition

of the electrical circuit through the coil, one of said time delay elements comprising a gas leakage device fixed with respect to one of said electrodes and the other comprising a relatively fixed mercury leakage device, and means including at least one of said time delay elements for causing the switch to have substantially quick operate reset characteristics.

5. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting the mercury level, cooperating time delay elements associated with one of said electrodes to delay the movement of mercury with relation to said electrode upon a change in the condition of the electrical circuit through the coil, one of said time delay elements comprising a gas leakage device fixed with respect to one of said electrodes and the other comprising a relatively fixed mercury leakage device, and means including at least one of said time delay elements for causing the switch to have substantially quick release reset characteristics.

6. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a fixed thimble telescoped over one of said electrodes and having a gas leakage device at its upper end and the other comprising a mercury cup extending around and above the bottom of said thimble and provided with a restricted wall opening for the timed passage of mercury, the gas leakage device associated with said thimble being relatively slow in its action as compared to the mercury passage associated with the cup.

7. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a fixed thimble mounted over one of said electrodes and having an opening for the passage of mercury and a top gas leakage device, and the other comprising a mercury cup extending around and above said side opening provided with a restricted wall opening for the timed passage of mercury, and said displacer being telescoped over the mercury cup whereby upward movement of the displacer causes an immediate drop in the mercury column within said cup.

8. In a mercury switch relay having prescribed operating characteristics, the combination of a relay coil, a switch associated with the coil, said switch comprising an envelope, spaced electrodes in the envelope, a mercury fill, a hollow displacer responsive to the coil for shifting

the mercury level, and cooperating time delay elements associated with one of said electrodes to delay the movement of mercury with relation to said electrode upon a change in the condition of the electrical circuit through the coil, one of said time delay elements comprising a gas leakage device fixed with respect to one of said electrodes and arranged to control the movement of mercury toward said electrode and the other one of said time delay elements comprising a mercury cup extending over a portion of said gas leakage device and provided with a restricted

wall opening for the time passage of mercury arranged to control the movement of mercury away from said electrode, said time delay element in said cup being faster in effect than said gas leakage time delay element, whereby the switch is characterized by a delayed make and a delayed break of the circuit through the electrodes and is further characterized by having a substantially quick reset at least for one direction of movement of the mercury. 10

CLARENCE E. GEHRAND.
